ATTORNEY

UNITED STATES PATENT OFFICE.

FREDERICK E. PRETAT, OF WATERBURY, CONNECTICUT, ASSIGNOR TO THE ROGERS & HAMILTON COMPANY, OF SAME PLACE.

DESIGN FOR A HANDLE FOR SPOONS, &c.

SPECIFICATION forming part of Design No. 22,747, dated August 29, 1893.

Application filed July 26, 1893. Serial No. 481,555. Term of patent 14 years.

To all whom it may concern:

Be it known that I, FREDERICK E. PRETAT, a citizen of the United States, residing at Waterbury, in the county of New Haven and 5 State of Connecticut, have invented and produced a new and original Design for Handles for Spoons, Forks, &c.; and I do hereby declare the following to be a full, clear, and exact description of the invention, such as will 10 enable others skilled in the art to which it appertains to make and use the same.

In the accompanying drawing I have shown a handle embodying my design.

The leading features of my design are, the 15 side edges of the handle extending upward parallel for a certain distance and thence diverging into wave lines which are symmetrical with each other, and thence curving regularly and uniformly to the top of the handle; 20 and the raised shell on the obverse side of the handle at the top, the opposite sides of the shell being formed by inward scroll-like formations leading on each side directly from the side edges of the handle, while the shell 25 at its inner or narrowest part describes a curve which extends abruptly from the upper end

of the handle, the entire shell pattern being raised in convex curves from the obverse side of the handle.

In the drawing, 1 is the handle, 2 the parallel side edges, 3 the symmetrical wave lines, 4 the regular and uniform curvatures at the top of the handle, 5 the shell, 6 the inward scroll-like formations on the opposite sides of the shell, and 7 the curved narrow portion of 35 the shell extending from the upper end of the handle.

In the drawing, in solid and dotted lines respectively, I have shown a spoon bowl and fork formed at the lower end of the handle, 40 and my newly invented design is applicable for the handles of spoons, forks, &c.

I claim—

The design for handles of spoons, forks, &c., substantially as shown in the accompanying 45 drawing.

In testimony whereof I affix my signature in presence of two witnesses.

FREDERICK E. PRETAT.
